UNITED STATES PATENT OFFICE.

EMIL THIEME, OF WARREN, OHIO.

COMBINED CURTAIN-POLE AND WINDOW-SHADE BRACKET.

1,131,571.

Specification of Letters Patent. Patented Mar. 3, 1915.

Application filed May 15, 1914. Serial No. 838,816.

To all whom it may concern:

Be it known that I, EMIL THIEME, a citizen of the United States, residing at Warren, in the county of Trumbull and State of Ohio, have invented new and useful Improvements in Combined Curtain-Pole and Window-Shade Brackets, of which the following is a specification.

The invention relates to a window fixture, and more particularly to the class of combined pole and shade roller holders or brackets.

The primary object of the invention is the provision of a holder or bracket wherein a curtain pole or shade roller or both can be supported from a window frame in proper position, relative thereto, the shade holder being adapted for folding movement to rest out of the way when not in use, while the pole holder can be detached when not in use.

Another object of the invention is the provision of a bracket or holder wherein the shade support and pole holder can be reversed so that the shade support or the pole holder can be placed at the outside or inside of the window casement.

A further object of the invention is the provision of a device of this character which is extremely simple in construction, reliable and efficient in use, strong, durable, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawing:—Figure 1 is a fragmentary front elevation of a window casement showing the bracket or holder constructed in accordance with the invention applied thereto. Fig. 2 is a perspective view of the said bracket. Fig. 3 is a sectional view on the line 3—3 of Fig. 1.

Similar reference characters indicate corresponding parts throughout the several views in the drawing.

Referring to the drawing in detail, the bracket or holder comprises a base plate 5, preferably made from sheet metal, although the same may be made from any other material. The plate 5 is slotted near one end to form ears 6 which are bent at right angles to the plate so as to be disposed in spaced parallel horizontal relation to each

other and form bearings for a removable pintle or pin 7 which is engaged therein and is adapted to form a pivot for a swinging or foldable shade bracket or holder 8 in which is adapted to be engaged the shade roller as usual, the holder or bracket 8 being formed with ears 9 at right angles thereto, and through which is passed the pintle or pin 7 for detachably and swingingly connecting the holder 8 to the base plate. Formed at the opposite end of the base plate 5 is a tongue or extension 10, the same being bent to form a socket 11 in which is detachably engaged the reduced end 12 of a curtain pole holder or support 13, the same being formed at its opposite end with a downwardly arched or bowed pole receiving bearing 14 in which is adapted to be seated the curtain pole of the ordinary well-known construction.

The base plate 5 is provided with screw or nail holes 15 so that the said base plate can be secured to the head of the window casement A, which is of the ordinary well-known construction.

It will be noted that on reversing the base plate 5 and removing the holder 8 and support 13 which are also adapted to be reversed, the same can be disposed at the inside or outside of the window casement as will be clearly obvious.

When the curtain pole support is used and it is desired not to use the shade roller holder the same can be folded inwardly against the window casement. Furthermore it is to be understood that when the shade roller holders are swung inwardly toward the sash of a window to lie against the window casement the curtain shade roller can be hung within the window casement so as not to project without the same, this being essential when hanging draperies, curtains, or the like.

From the foregoing it is thought that the construction and manner of use of the device will be clearly understood, and therefore a more extended explanation has been omitted.

What is claimed is:—

1. A device of the class described comprising a base plate having spaced ears at one shorter edge thereof and at right angles to the plane of the same, an extension formed at the other shorter edge of the plate and bent to form a socket, and a curtain shade

bracket swingingly connected to the said ears whereby the same can be projected beyond either face of the base plate.

2. A device of the class described comprising a base plate having spaced ears at one shorter edge thereof and at right angles to the plane of the same, an extension formed at the other shorter edge of the plate and bent to form a socket, a curtain shade bracket swingingly connected to the said

ears whereby the same can be projected beyond either face of the base plate, and a pole support insertible in the socket from either end thereof.

In testimony whereof I affix my signature in presence of two witnesses.

EMIL THIEME.
